UNITED STATES PATENT OFFICE.

LUTHER D. LOVEKIN, OF PHILADELPHIA, PENNSYLVANIA.

WATER-HEATER.

1,107,534.

Specification of Letters Patent. Patented Aug. 18, 1914.

Application filed November 23, 1912. Serial No. 733,033.

To all whom it may concern:

Be it known that I, LUTHER D. LOVEKIN, a citizen of the United States of America, residing in the city and county of Philadelphia, in the State of Pennsylvania, have invented a certain new and useful Improvement in Water-Heaters, of which the following is a true and exact description, reference being had to the accompanying drawings, which form a part thereof.

My present invention relates to water heaters and boilers, and the primary object of the invention is to provide an improved gas fired heater for heating water for domestic purposes, by what is commonly known as the storage system, as distinguished from the well known instantaneous hot water heating system.

More specifically, my invention has for its object to provide a heater characterized by its inherent simplicity and low cost of construction, and by the fact that it contains a minimum number of parts apt to get out of order from corrosion or otherwise, and by the fact that it contains no internal pipes liable to become foul.

The instantaneous hot water heaters, while in general use, are open to certain important practical objections, which have long been clearly recognized. For one thing, such a heater requires large gas fittings, in order that the heating may proceed with the proper rapidity, and when a number of such heaters are connected to the same gas supply pipe, this pipe must be considerably larger, to avoid an unsatisfactory drop in pressure when several of the heaters are simultaneously in operation, than the total amount of the gas would otherwise necessitate.

An instantaneous water heater is also materially more expensive in first cost than a storage system heater adapted to supply the same demand for hot water. Notwithstanding these distinct and clearly recognized objections, the instantaneous heating system has heretofore been largely preferred to the storage system, because of the substantially greater efficiency in gas consumption of the instantaneous system heaters as compared with the storage system heaters as these have heretofore been constructed.

I have been able, and my present invention consists of features of construction and arrangement by which I accomplish this, to provide a gas fired storage system heater

which, while possessing the characteristic advantages of simplicity and low cost of storage system heaters, will give an efficiency in gas consumption equal to that obtained with the instantaneous heaters.

The various features of novelty which characterize my invention are pointed out with particularity in the claims annexed to and forming a part of this specification. For a better understanding of my invention, however, and the advantages possessed by it, reference should be had to the accompanying drawings and descriptive matter in which I have illustrated and described various forms of apparatus embodying my invention.

Of the drawings: Figure 1 is an elevation, partly in section, of a preferred form of water heater; and Fig. 2 is a partial sectional plan taken on the line 2-2 of Fig. 1.

In the drawings, A represents the tubular shell of a water heater suitable for domestic use. The upper end of the shell A is closed by the end member A'. The latter is formed with a central flanged aperture, in which is riveted or otherwise suitably secured, the upper end of a tubular member comprising an upper corrugated section B and a lower uncorrugated section C. The section B, which is substantially smaller in diameter than the shell A and is centrally disposed in the latter, has its lower end passed through an aperture in the upper end of and secured to the section C. The body portion of the section C is substantially larger in diameter than the section B, and at its lower end the section C is expanded to provide a flange C' which fits against the inner wall of the shell A, and is secured to the latter.

The annular space D inclosed by the shell A and surrounding the central tubular member, forms the water space of the heater proper, and D' and D² represent the water inlet and water outlet thereof. Below the lower end of the tubular member is located the gas burner F, which, preferably, as shown, is surrounded by the lower portion of the shell A, the latter being provided with suitable openings, not shown, for the admission of air to support combustion, and being provided with a door A², normally held by a spring hinge A³ in the position in which it closes the doorway through which the main burner F, or a pilot burner, may be ignited. The space E inclosed by the section C forms

the main combustion chamber of the heater and the section B serves as a flue for conveying the gas products of combustion out of the combustion chamber. To delay the passage of the hot products of combustion through the flue section B a retarder G is employed. As shown, this consists of a helix formed by twisting a thin metal bar of a width approximately equal to the interior diameter of the section B. Advantageously the section B is turned in and up at its lower end to provide a channel B' in which the moisture depositing in the inner wall of the flue and running down the latter may collect. Surrounding the central tubular member but separated therefrom by an annular space H' of substantially uniform thickness, is a tubular member H, which preferably is formed of copper and extends from a few inches above the bottom of the space E to within a foot or so of the top of the chamber D. As shown, the member H is formed of cylindrical sections H' and H² and a conical connecting section H³. H⁴ represent supports secured to the lower end of the section H², and H⁵ are brackets attached to the section H² and serving to center the upper end of the member H. In the case of a domestic heater of the ordinary dimensions, as for instance one in which the total depth of the chamber D is five feet, the internal diameter of the shell A is thirteen inches, the external diameters of the sections B and C, respectively, are three and seven inches; the internal diameter of the upper portion of the member H should be about four inches and the internal diameter of the lower and larger portion should be about eight inches.

40 The upper end of the flue section B may be connected directly to the chimney, or where a maximum efficiency is desired, I connect it by the pipe I to the top of an economizer comprising a tubular shell J, including a coil of pipe L, through which the water to be heated in the main heater is passed to the water inlet D' of the latter. A pipe M connected to the lower end of the economizer J may run to a convenient chimney.

45 In operation, when the gas is ignited at the burner F, the member H causes a vigorous circulation of water to take place within the water space in the direction indicated by the arrows in Fig. 1. The water entering the annular space H' freely at the lower end of the latter rapidly rises in temperature as it passes upward, and by reason of this rise in temperature, is caused to move rapidly to the upper end of the space H' where it has a free outlet into the water space D proper. The rapid flow of the water in the space H' along the outer wall of the combustion chamber and flue increases the rate at which heat is abstracted by the water

and hence adds to the efficiency of the apparatus. Furthermore, this circulation results in a practical uniformity of temperature in all parts of the water space, except for a small "hot pocket" in the upper end of the space D. This general uniformity in temperature is highly desirable, because it avoids fluctuations in the temperature of the water drawn off and also because it adds to the rapidity and efficiency with which the water absorbs heat by preventing any portion of the heating surface from being bathed by a stagnant or slow moving body of water at a high temperature, and hence unable to absorb heat from the heating surfaces as rapidly as would a cooler body of water. The small hot pocket at the extreme top of the space is also advantageous. The size of this pocket depends on and increases with the distance between the tops of the space D and the top of the member H. The use of circulation member H results in an increase of the practical efficiency of the apparatus of a radical character. In careful and long continued tests of my improved heater in comparison with other storage system heaters of the same capacity, my heater has shown an efficiency of from eighty to eighty-five per cent. as compared with an efficiency of from sixty to sixty-five per cent. in the case of the older forms of storage system heaters. The retarder G by prolonging the path for the hot products of combustion is a factor, though a minor factor, in the increased efficiency which I obtain with the heater shown. It will be observed that there are several times the number of corrugations in a given length of the tube B as there are turns of the helix into which the bar G is twisted in a corresponding length of said bar. In consequence the heating fluid passing through the tube B is caused to flow along a generally spiral path by the retarder G. The fluid is thus continually impelled by centrifugal force against the wall of the tube and this materially augments the effect of the corrugations of the tube B in breaking up the stream lines, and thereby materially increases the effectiveness of the heat transfer between the fluid and the tube. The economizer J, which may or may not be employed, when used adds to the efficiency of the apparatus by abstracting otherwise waste heat from the hot gases after they leave the heater proper.

50 The tubular parts B and C, which preferably are formed of copper, may each be plain cylinders, or they may both be corrugated, but preferably, as shown, the section B is and the section C is not corrugated. Where the parts B and C are corrugated, the thickness of the space between the crest of the corrugation ribs and the inner wall of the member H may be slightly less than

where the members are plain cylinders. The use of such corrugated members adds somewhat to the efficiency of the heater by breaking up the ascending stream of water passing through the space H' but the effect of such corrugations is substantially less marked where the member H is employed than it would be if the member H was omitted.

10 While in accordance with the provisions of the statutes I have illustrated and described the best forms of my invention now known to me, it will be apparent to those skilled in the art that changes may be 15 made in the form of the apparatus disclosed without departing from the spirit of my invention, and that under some conditions certain features of my invention may be used without a corresponding use of other 20 features.

Having now described my invention, what I claim as new and desire to secure by Letters Patent, is:

1. In a water heater of the kind specified, 25 the combination of a tubular part enlarged at its lower end and serving as a combustion chamber and flue, a tubular shell surrounding the first mentioned part and connected to the ends of the latter to form a 30 water chamber, and a tubular member located within said water space and comprising a large diameter portion surrounding the enlarged lower end of said tubular part and a portion of smaller diameter surrounding 35 the upper portion of said part, said member being spaced away from the lower end wall of the water space a distance sufficient to permit a free flow of water into the annular circulating passage between said tubular 40 part and said tubular member and being spaced away from the upper end of said space a distance somewhat greater than the first mentioned distance whereby a hot

pocket is formed in said space above the upper end of said tubular member.

2. In a water heater of the kind specified, the combination of a tubular part enlarged at its lower end and having a smaller upper corrugated portion, said part serving as a combustion chamber and flue, a tubular shell 50 surrounding the first mentioned member and connected to the ends of the latter to form a water chamber, a tubular member located within said water space and comprising a large diameter portion surrounding the enlarged lower end of said tubular part and a portion of smaller diameter surrounding 55 the upper portion of said part, said member being spaced away from the lower end wall of the water space a distance sufficient to permit a free flow of water into the annular 60 circulating passage between said tubular part and said tubular member and being spaced away from the upper end of said space a distance somewhat greater than the 65 first mentioned distance whereby a hot pocket is formed in said space above the upper end of said tubular member, and a spiral retarder disposed in the smaller upper portion of said tubular part and having 70 fewer turns per unit of length than there are corrugations in a corresponding length of the corrugated portion of said tubular part.

3. In combination, a corrugated tube and 75 means for augmenting the transfer of heat between said tube and a fluid flowing through the latter, comprising an element axially disposed in said tube and adapted to give the fluid passing through said tube a tendency to follow a spiral path comprising 80 a smaller number of turns than there are corrugations in said tube.
